[57] CLAIM

The ornamental design for a container for transportation of cryogenic gases, as shown and described.

DESCRIPTION

FIG. 1 is a front and side perspective view of a container for transportation of cryogenic cases showing my new design.

FIG. 2 is a rear and side perspective view thereof, opposite than seen in FIG. 1;

FIG. 3 is a front elevational view thereof with a door lifted up; and

FIG. 4 is a bottom plan view thereof.

FIG. I

FIG. 2

FIG.3

FIG.4
